APPARATUS FOR CEMENTING WELLS

Filed Feb. 23, 1937

FIG. 2

INVENTOR: Johan Willem Klomp
BY HIS ATTORNEY: Bartholomew

UNITED STATES PATENT OFFICE

2,164,190

APPARATUS FOR CEMENTING WELLS

Johan Willem Klomp, Boldesti, Rumania, assignor to Shell Development Company, San Francisco, Calif., a corporation of Delaware

Application February 23, 1937, Serial No. 127,058
In Rumania March 3, 1936

4 Claims.

(Cl. 166—1)

This application pertains to the art of cementing wells and relates more particularly to a method and apparatus for cementing liners which are not supported by a string of casing extending to the surface.

When cementing a liner, the use of that portion of the casing which extends to the surface and serves only to support the liner may sometimes be dispensed with by attaching the liner to the end of a drill pipe, lowering it therewith into the borehole, pumping the desired amount of a fluid cement mixture through the drill pipe, and pumping a fluid under pressure after the cement charge to force the latter out of the liner, thereby cementing the liner.

This method of operation presents, however, some serious disadvantages. First, the cement mixture cannot be prevented from mixing with the pressure fluid (usually mudflush) which is used to force it into the space between the liner and the walls of the borehole. Second, it is difficult to determine with any degree of accuracy the moment at which the cementing mixture is completely displaced from the liner, and at which the pumping of the pressure fluid should be stopped in order to avoid dilution of the cementing mixture outside the liner with mud.

It is, therefore, the object of the present invention to provide a method of cementing liners supported by drill pipe strings wherein the cementing fluid is forced out of the liner by means of a piston actuated by a pressure fluid, the mixing of the two liquids within the liner being thereby prevented.

It is another object of the present invention to insure a better control of cementing operations by providing the operator with means for determining accurately the moment at which substantially the whole cementing charge has been forced out of the liner and further pumping of the pressure fluid can be stopped.

Other objects and features of this invention, as well as the method and the preferred apparatus for practicing the same will be better understood from the following description taken with reference to the appended drawing wherein:

Fig. 1 is a diagrammatic elevation view, partly in cross section of a liner lowered into a borehole and provided with a device by means of which it can be cemented through the drill pipe. Fig. 2 shows a preferred form of a sealing body to be dropped into the drill pipe to operate the device of Fig. 1.

Referring to Fig. 1, 1 indicates a borehole into

which a string of drill pipe 2 has been lowered. An adapter 4 is attached to the lower end of the drill pipe by means of screw-threads 3. The lower end of the adapter is provided with external screw-threads 5, which are preferably left-handed and serve to connect the adapter with a collar 6, which in turn supports, by means of screw-threads 11, the liner 14, which is to be cemented.

A nipple 7 is screwed into the lower part of the adapter 4 and is attached by means of framable pins or rivets 8, made of a suitable material such as brass, copper, etc., to a hollow mandrel 9, also made of brass, copper, aluminum, etc. The axial bore through the mandrel 9 is provided with a constriction 10, adapted to serve as a seat to the sealing body, such as shown in Fig. 2, which may be dropped through the drill pipe. A piston or packer 12, made of rubber, leather, wood, laminated canvas sheets or any other suitable material and adapted to fit slidably within the liner 14 is attached to the mandrel 9, for example, by means of serrations 15 carried by the mandrel 9. The periphery of the packer may be provided with recesses 13 to insure a tighter fit between the packer and the liner. The lower portion of the liner or of the liner string is provided at a desired depth with a constriction or other means for limiting the downward stroke of piston 12, such, for example, as plug 17, having a fluid passage 16 adapted to be closed by a non-return valve 18, seating upwards. The plug 17 may be constructed in any desired form, for example as an adapter to which another liner, such as the perforated liner shown at 21, may be attached.

In operation, the following procedure may be followed:

A liner string of suitable length is made up at the surface and lowered into the borehole at the end of a drill string to the place where it is to be cemented.

The necessary quantity of fluid cement mixture which can be readily calculated from the known dimensions of the borehole and of the liner, is then pumped down through the drill pipe and is followed by a charge of pressure fluid, such as mudflush, to force the cement out of the drill pipe and liner. At the moment when the pumping is switched at the surface from cement to mudflush, a sealing body, such as shown in Fig. 2 is dropped into the drill pipe. This sealing body is of a diameter such as to pass through the drill pipe, and has a specific gravity greater than that of the mudflush, but less than that of

the cementing mixture, being therefore adapted to keep at the interface of the two fluids. The sealing body may be a suitably weighted hollow metallic ball or a ball made of a composition material of suitable specific gravity. If a drill pipe having externally upset couplings of the flush-joint type is used, the sealing body may be given the shape of a small piston provided with rubber packing as shown in Fig. 2.

10 The sealing body, being of a diameter only slightly smaller than that of the drill pipe, prevents any appreciable mixing of the cement with the pressure fluid within the drill pipe, in which it travels downwards at the interface of the two fluids.

15 When the cementing mixture has been forced out of the drill pipe into the liner by the action of the pressure fluid, the sealing body comes to rest against the seat 10 in mandrel 9. The rise 20 in pressure due to the closing of the axial passage through the mandrel 9 is sufficient to shear off the rivets 8 attaching said mandrel and the piston 12 to the nipple 1, whereupon the piston 12 moves downwardly under the action of the 25 pressure fluid and forces the cement mixture out of the liner. In some cases, the rivets 8 may be dispensed with, the piston 12 being retained in its uppermost position by friction against the walls of liner 14 during the time when the cementing fluid is being pumped down.

30 When the piston 12 reaches the end of its desired stroke its further motion is stopped by the plug 17, and the resulting rise of pressure indicates to the operator that the desired amount of 35 the cement charge has been forced out of the liner. The pumping of the pressure fluid is therewith stopped, the non-return valve 18 preventing an upward return of the cement mixture into the liner which is sometimes caused by formation 40 back-pressure. The cemented liner may be readily disconnected from the drill pipe by suitably rotating the latter, the adapter 4 being, as stated above, attached to the collar 6 by means of left-hand screw-threads.

45 I claim as my invention:

1. In an apparatus for cementing wells, a pipe string, a liner attached to the end thereof, a piston yieldably held within the upper portion of the liner, a fluid passage through the piston means for placing a cement charge below the piston through said passage, means for closing said passage, and means for applying to the upper face of said piston a sufficient fluid pressure to move the piston downward when the passage

therethrough is closed, said piston being effective in forcing out of the liner the cement charge placed below its lower face.

2. In an apparatus for cementing wells, a pipe string, a liner attached to the end thereof, a piston fitting within the upper end of the liner, frangible means for retaining said piston in its uppermost position, a fluid passage through the piston, means for placing a cement charge below the piston through said passage, means for closing said passage, a plug within the lower portion of the liner, a fluid passage through said plug, and means for applying to the upper face of the piston a sufficient fluid pressure for breaking said frangible means and moving the piston 15 downwards when the fluid passage therethrough is closed, said piston being effective in forcing out of the liner the cement charge placed below its lower face.

3. In an apparatus for cementing wells, a pipe 20 string, pumping means to force a cement charge and a pressure fluid down said string, a liner attached to the end of said string, a piston yieldably held within the upper portion of the liner, a fluid passage through the piston for placing a cement charge below the piston, floating means maintained by gravity at the interface between the cement and the pressure fluid for closing said passage, said pumping means being adapted to apply to the upper face of said piston a sufficient fluid pressure to move the piston downwards when the passage therethrough is closed, said piston being effective in forcing out of the liner the cement charge placed below said piston.

4. In an apparatus for cementing wells, a pipe 25 string, pumping means to force a cement charge and a pressure fluid down said string, a liner attached to the end of said string, a piston yieldably held within the upper portion of the liner, a fluid passage through the piston for placing a cement charge below the piston, floating means maintained by gravity at the interface between the cement and the pressure fluid for closing said passage, said pumping means being adapted to apply to the upper face of said piston a sufficient 30 fluid pressure to move the piston downwards when the passage therethrough is closed, said piston being effective in forcing out of the liner the cement charge placed below said piston, and means carried by the liner to arrest the downward motion of the piston, thereby causing a rise in the pressure of the fluid within the string.

JOHAN WILLEM KLOMP.
